UNITED STATES PATENT OFFICE.

AUSTIN GUDMUNDSEN AND FRANK E. DOLE, OF SALT LAKE CITY, UTAH.

LAUNDRY PIN.

Application filed April 21, 1924. Serial No. 707,783.

To all whom it may concern:

Be it known that we, AUSTIN GUDMUNDSEN and FRANK E. DOLE, citizens of the United States, residing at Salt Lake City, in the county of Salt Lake and State of Utah, have invented certain new and useful Improvements in Laundry Pins, of which the following is a specification.

Our invention relates to sorting devices used in laundry work and has for its object to provide a new, economical and conveniently operated pin which is detachably fastened in articles of clothing for marking said articles while they are being washed in laundries.

A further object is to provide a locking laundry pin from which articles may be suspended, and from which said articles may be detached by a simple lateral movement of either the articles or the pins while the articles or pins are bunched, and to facilitate the assembling of the pins in their cases.

These objects we accomplish with the device illustrated in the accompanying drawings in which similar letters of reference indicate like parts throughout the several views, and as described in the specification forming a part of this application and pointed out in the appended claims.

In the drawings in which we have shown the best mode of applying the invention to practical and beneficial use, Figure 1 is a view in perspective of one of the pins on a supporting rod, with articles of clothing suspended from the hook portion. Figure 2 is an elevation of the device, with the hook closed. Figure 3 is an elevation of the device showing the reverse side from that shown in Figure 1 and with the hook open. Figure 4 is a plan view showing top or end remote from the hook. Figure 5 is detail in plan of the hook portion of the device.

The device consists of a thin metal plate A having an opening B medially therein which is shaped to conform with the shape of the supporting rod R on which the pin and clothing thereon are suspended. A guide case C is provided by bending portions of said plate A to form a rectangular case. The sides of said guide case are spaced apart to allow the flat end portion of the hook to slide freely in said case. In the outer edge of said guide case C two recesses D and E are cut. On the opposite edge of said plate A a hook point case is provided

by bending other portions of said plate A to form the sides and ends, as shown at G, and said case G is extended from the body of said plate A as an integral wing portion to allow the hook point to be engaged when the clothing is suspended thereon.

The hook portion of my invention is a flat thin metal shank F in which an elongated slot 1 is provided and which opens to the edge and near one end of the said shank. A catch 2 is formed on the free end portion of said shank F which engages in the respective recesses D and E as said shank is operated. The other end portion of said shank F is formed into a hook H, the end of which is tapered and sharpened to form a point which engages in said case G when the clothing is to be held on the hook. The said hook H is formed or bent with a short curve 3 nearest the shank F with the other portions having less curvature, as at 4, in order that the tendency of clothing suspended from said hook will be to slide toward the shank F rather than off of the hook. A guard plate K, having a laterally projecting rib 5, is secured at one end adjacent each of the rods R, and parallel thereto.

The operation of our device is as follows:

The hook portion of the device is independently constructed, as shown in Figure 5, and its shank portion F is slipped into the guide case C by a slight flexing of the catch portion 2; the said shank is made of spring metal to allow the bending required. The flattened shape given to the shank F and guide case C will position the point of the hook in alinement with the case G, and when the catch 2 is in the recess E the hook point will be spaced far enough from the said case G to allow articles of clothing to be impaled on or engaged with said hook H. The shank F, with its integral hook H, is then moved longitudinally toward the said plate and the catch 2 engaged in the recess D, and when so engaged the point of the hook will be engaged in the case G and the clothing held on the hook. After the clothing has been laundered the devices are suspended from the supporting rod R by slipping the device over the free end of said rod F, with the said rod through the opening B. When all of the articles of one bunch of laundry are thus suspended on one rod, the devices will be bunched and may be

2
grasped with one hand by the operator while the bunch of laundered clothing is held with the other hand. Then, by a lateral movement of the clothing, each of the devices will 5 be partially rotated on the rod R, and the catches 2 will all be brought into contact with the rib 5 on the guard plate K, where- by the catches 2 will be released and pushed from the recesses D, and the shanks F, with 10 their hooks H, will be slid downwardly and the clothing released from the hooks, and the catches 2 will engage in the recesses E. The pins are then open and ready for placing in their respective cases.

15 Having thus described our invention we desire to secure by Letters Patent and claim:-

1. A laundry pin comprising a plate portion with a hole centrally therein and adapted to be placed on a supporting rod; a guide case on one edge of said plate having two spaced apart recesses opening to its interior; a hook having a slotted shank adapted to slide longitudinally in said guide case; a 25 catch formed on one leg of the slotted portion of said shank; a hook point case formed

by other portions of said plate and adapted to receive the point of said hook.

2. A laundry pin comprising a plate having an opening centrally therein; a guide case near one edge of said plate and having recesses opening to its interior; a hook having a shank longitudinally movable in said guide case and the point of the hook adapted to engage in the point case; and a portion of said shank adapted to engage in either of said recesses.

3. In a laundry pin comprising a plate having an opening centrally therein; a guide case integrally formed thereon and having a recess opening to its interior, and said guide case having spaced apart slots on its outer side; a hook member having a shank portion longitudinally movable in said guide case and adapted to engage in said spaced apart slots; and another portion of said hook member formed into a pointed hook.

In testimony whereof we have affixed our signatures.

AUSTIN GUDMUNDSEN.
FRANK E. DOLE.
